RECOVERY OF TAR ACIDS FROM TAR

Stuart Parmelee Miller, Englewood, N. J., assignor to The Barrett Company, New York, N. Y., a corporation of New Jersey

Application August 6, 1929, Serial No. 383,859

10 Claims. (Cl. 260—154)

This invention relates to an improved process for the recovery of tar acids from tar, whereby the tar acids can be recovered directly from the tar instead of from distillate oils produced from 5 the tar.

The common method of recovering tar acids or phenols from tar is to distill the tar and extract the tar acids from the distillates with a caustic soda solution. A large amount of distillate must 10 be handled in most cases to produce a relatively small amount of tar acids. Where the tar acids are extracted at a plant remote from the tar distillation plant, the cost of transportation of the distillate oil is an added expense. Tar acids can 15 not be directly extracted from tar with caustic soda solutions in a satisfactory manner.

The present invention provides an improved process for recovering tar acids from tar whereby the tar acids can be directly recovered without 20 the necessity of producing a large amount of distillate oil and washing or extracting such distillate oil with caustic soda solutions.

According to the present invention, inert gases or vapors are passed through or into intimate 25 contact with the tar while it is in a heated condition to effect vaporization of tar acid oils, and the resulting admixed gases and vapors are brought into contact with an alkaline solution, e. g. a caustic soda solution, to extract the tar acid vapors.

The inert gases, after they have been employed 30 for the vaporization of tar acid oils and after the tar acid vapors have been extracted by the caustic soda solution, can advantageously be recirculated through the tar in a cyclic manner and employed over and over again for vaporizing tar acid 35 oils from the tar, followed by extraction of tar acid vapors from the admixed gases and vapors. In such recirculation process, the tar and the caustic solution can both be kept at the same or 40 similar temperatures, and the gases can be recirculated through insulated lines so that the entire operation is carried out with a minimum of heat loss and with the circulating gases maintained at a uniform temperature, or at temperatures 45 which do not vary greatly during the recirculation.

The inert gas or vapor which it is considered particularly advantageous to employ in the present process is steam which, at temperatures above 50 its condensation point, acts as an inert gas or vapor, and can be passed through the tar and through the caustic solution and recirculated at such temperatures without condensation, or without any considerable condensation. Air or inert gases such as nitrogen, fuel gas, etc. may be used

in the recirculation process. When air is employed, any oxidizing effect which it may exert will be limited to the preliminary period of recirculation. Similarly, fuel gas, when used in an unpurified state, will be purified during the early stages of the process. When the same gas is recirculated over and over again, only such additional amount of gas need be added as is required to make up for losses and for such gases as may be drawn off from the circulating system, e. g. 10 through condensers. When the process is not operated as a recirculation process, the gases and admixed oil vapors, after the extraction of tar acid vapors, can be cooled to condense any neutral oils which may be carried by the gases. So also, 15 when the gases are recirculated, the admixed gases and oil vapors leaving the caustic soda absorber, may be somewhat cooled to condense neutral oils therefrom, and the gases then reheated for further use in the recirculatory process. The 20 vaporization of tar acid oils from the tar will result in vaporization not only of tar acids or phenols, but also of varying amounts of neutral oils or hydrocarbons which will remain as vapors unless 25 condensed from the admixed gases by cooling. If such condensation does not take place, and if the gases and admixed vapors are recirculated, the recirculated gases and vapors will be made up 30 in part of inert gas and in part of neutral oil vapors. Part of the neutral oil vapors can be 30 condensed and neutral oil recovered by cooling the recirculating gases, or by drawing off part of the admixed gases and vapors from the circulating system and supplying additional inert gas as required. Or the process may be operated so 35 that the gaseous circulating medium consists entirely of oil vapors maintained above their condensation temperature.

The tar which is subjected to the dephenolizing treatment should be heated to a suitable temperature, for example, somewhat above 100° C., before the inert gases are brought into contact therewith, although this will depend upon the quantity of gas recirculated per unit of tar acids recovered. The tar may be preheated to the required temperature by the use of a steam preheater or by the use of waste heat from the flue gases in the flues at coke or gas plants, or by the use of waste flue gases from tar stills, steam boiler plants, etc., or by the use of heat inter- 50 changers in which hot tar or pitch is employed as the heating medium, or by separate heating stills, etc.

Where the recovery of tar acids from the tar is carried out at coal distillation plants at which 55

coal tar is produced, such as coke oven plants or gas plants, the tar separated from the gases at an elevated temperature, may be kept hot and employed in a heated condition. In many cases the temperature will be sufficient for carrying out the tar acid removal process without added heat or at least without any substantial amount of heat. Where the collector mains of a coke oven plant are operated at high temperature with the use of hot tar for flushing the main, the hot tar drawn off from the main may be at a sufficiently high temperature so that it does not require further heating, and so that it can be led directly from the main to the apparatus for the removal of tar acids.

In the distillation of tar, where the tar must be heated to a high temperature, the removal of tar acids according to the present invention, can advantageously be combined with the distillation, for example, by passing a current of inert gas through the tar after it has been pre-heated to the proper temperature and before it is subsequently heated to a higher temperature for the main distilling operation. In the case of an ordinary tar still containing a large batch of tar, the still can be heated until the tar is at the proper temperature and inert gas can then be circulated through the tar, and the resulting gases and vapors passed through the caustic soda solution and the gases recirculated until the tar acid oils have been driven off to the desired extent, after which the recirculation can be stopped and the still heated to a higher temperature to effect distillation of the dephenolized tar. Where the tar is distilled in a pipe coil still with heating of the tar in a pipe coil and discharge of the heated tar into a vapor box or vapor separating chamber, the initial heating of the tar can be so regulated that the tar will be at the proper temperature in the vapor separating chamber and current of inert gases can be passed through the tar in such chamber to remove tar acid oils, after which the dephenolized tar can be heated to a higher temperature by circulation through another pipe coil which discharges into another vapor separating chamber, etc.

For effective removal of tar acids from the tar, it is important that the inert gas or vapors should come into intimate contact with the tar. This can be accomplished in suitable scrubber towers or other types of scrubbers. Any suitable type of scrubber or dephenolizer may be used so long as it provides intimacy of contact between the tar and the inert gas. A scrubber such as a well packed tower which provides for satisfactory degree of countercurrent contact, is well suited for use. Scrubbers in which the tar is sprayed or atomized into the inert gas may also be employed, but in such case it will usually be desirable to recirculate the tar or repeatedly spray or atomize it into the gas in such large volume as will bring all parts of the tar into contact with the inert gas so that the tar acids and attendant oils may be vaporized therefrom. Less efficient types of scrubbers can be employed, and, where the removal of tar acid and oil vapors with inert gas is combined with distillation of tar, the inert gases can be passed through the tar still, in the case of the still containing a batch of tar, or through the vapor box of a pipe coil still, etc.

The scrubber or extractor employed for removing tar acid vapors from the mixture of gases and vapors may be of any suitable type, such as the types mentioned in connection with the tar scrubber, or the gases may be passed through

caustic solution in a tank. Those parts of the extractor with which the caustic liquid comes in contact should be constructed of a caustic-resistant material.

The removal of tar acids from the tar can be carried to the point where the tar is practically completely stripped, or nearly stripped, of tar acids, or to the point where only the lower boiling acids, e. g. the phenols and the cresols are removed and recovered. A partial removal of the more readily vaporizable tar acids can be effected without removing the higher boiling and more difficultly removable acids. So also, the removal can be carried out in stages, for example, by passing the tar through a series of scrubbers where it is scrubbed by the inert gas, and with recirculation of the inert gas from one scrubber through the tar acid absorber and back to the same scrubber. In such multi-stage extraction of tar acids, the carbolate solutions produced will vary from each other, the carbolate solution from the first scrubbing operation giving a carbolate richer in lower boiling tar acids, while those from the successive scrubbing treatments will give carbolate solutions richer in higher boiling acids.

The tar subjected to the dephenolizing treatment of the present invention, may be ordinary coal tar from coke oven or gas retort plants, or it may be a heavier tar fraction or a lighter tar fraction, such as the heavier tar collected from the collector main of a coke oven plant, or the lighter tar or tarry oil recovered in the condensing system of a coke oven plant. Tars from various gas retort plants, including vertical retort plants, and low temperature tar, etc., can be subjected to treatment for the recovery of tar acids therefrom, according to the present process. In many cases, particularly at coke oven plants, it will be of advantage to treat only the lighter tar or tarry oils separated in the condensers, since this lighter tar contains a much higher proportion of tar acids than the heavier tar separated in the collector main. The lighter tar from the condensers may represent only around 25 to 35% of the total tar, yet it ordinarily contains around 50 to 65% of the total tar acids.

When employing the recirculation process of the present invention, the only oil removed from the recirculating gases, in addition to the tar acids absorbed in the caustic solution, will be the oils dissolved in the carbolate solution, or such as may be condensed in the caustic absorber. Neutral oil vapors will be formed or separated from the tar during the recirculation of the gases, but these neutral oil vapors will be carried back with the inert gases through the tar where the oil vapors may be in part reabsorbed, or where their presence will retard and limit the further vaporization of neutral oils, resulting in a selective vaporization of tar acid oils from the tar. In such case, the recirculating gases will be admixed with neutral oil vapors. Since neutral oil vapors will be carried in the gases, in such recirculatory system, such neutral oils may be recovered from the circulating gases, after they have passed through the tar acid absorber. In such cases, the caustic scrubber or tar acid absorber may be followed by fractional condensation to condense part of the neutral oil vapors. Naphthalene oil vapors may be recovered in this manner.

The rate at which tar acids can be removed from the tar depends upon several factors, e. g., the temperature to which the tar is preheated, the relative volume of steam or other inert gas

- recirculated, the temperature of the gases recirculated, etc. If the tar is highly preheated, e. g., to 175-200° C., it will be above the temperature at which oil vapors normally will form and flash away from the tar as it enters the scrubber. In such a case, if it is desired to have the dephenolized tar leaving the system retain all the neutral oil vapors, the gases leaving the tar scrubber must be cooled somewhat and the oils condensed must be returned to the dephenolized and partially distilled tar after it leaves the scrubber.
- It may be desirable also to somewhat cool the dephenolized and partially distilled tar prior to returning the oils to it. The recirculating gases may be cooled prior to, during, or following their passage through the caustic absorber. If cooled prior to passage through the caustic, the oils condensed will contain tar acids and should, if maximum recovery of tar acids is desired, be passed into the caustic absorber before they are returned to the tar. These acid bearing oils may, of course, be removed from the system, extracted with caustic and then returned to the partially distilled tar.
- Oil vapors will in many cases serve satisfactorily as the gaseous medium employed for removal of the tar acids from the tar. This will particularly be the case with tars containing lower boiling oils, e. g., tars containing benzol, toluol and the xylos. By heating the tar to the point at which these lower boiling oils are vaporized, the vapors may be recirculated through the tar and the caustic solution. These oil vapors serve as the inert gases employed in my process.
- Where waste steam is available, such as exhaust steam, or where steam is otherwise available at sufficiently low cost, the process can be carried out as a steam distillation process without recirculation of the steam. In such case, the steam will be passed through a suitable scrubber tower or other device for driving off tar acid oil vapors from the hot tar and the admixed vapors and steam will then be passed through a caustic scrubber to remove the tar acids after which the steam leaving the caustic absorber may be condensed, together with the neutral oil vapors, and the neutral oils recovered as a condensate. These neutral oils, recovered in this way, may be kept separate, or may be returned to the tar.
- In carrying out the recirculation process, the recirculated steam or other gas or vapor may if required be reheated or superheated before entering the tar scrubber or before entering each of the scrubbers. The tar scrubber or the caustic scrubber or both may be heated. The system should be well insulated to minimize heat losses. Where the recirculated gases are reheated, various heating means can be employed, such as those hereinbefore referred to in connection with the heating of tar. Where steam or other gases are recirculated, additional steam or gas will be supplied as required to make up for losses by condensation or otherwise and for such amounts of gas as may be drawn off from the circulating system, for example, for the purpose of condensing neutral oil vapors therefrom; any excess steam that may accumulate at high temperatures may similarly be drawn off from the recirculating gases, e. g., steam which accumulates as a result of treating wet tar by my process.

The caustic solutions employed for scrubbing tar acid vapors from the gases, may be ordinary caustic soda solutions of suitable strength. Caustic potash or sodium sulfide solutions may also be

employed in some cases. Where the gases and vapors passing through the caustic scrubber are at a much higher temperature than the caustic soda solution, the gases will be cooled by contact with the solution and the solution itself will be heated and may be concentrated by evaporation of part of the water. In this way, relatively dilute caustic soda solution may be employed and concentrated carbolite solutions produced. The strength of the carbolite solution made in the caustic absorber may thus be regulated, either by regulating the strength of the caustic soda solution employed, or the temperature of the scrubber or the temperature of the gases and vapors passing through the scrubber. If any steam is allowed to condense on its way through the scrubber, the carbolite will be diluted, while by maintaining the gases and the scrubber at a regulated temperature, any particular strength of carbolite solution that is desired may be produced. It will be understood that the tar acids contained in vapor form and carried by the gases will combine with the sodium or other metal of the caustic solution to form sodium or other metal phenolates, which will remain in solution with the excess caustic soda until the absorbing capacity of the solution is exhausted or reduced to the desired point.

In some cases it will be desirable to operate with relatively high temperature in the tar scrubber. In such a case the steam or other inert gas will pass at high temperature to the caustic absorber. To avoid evaporation of the caustic or carbolite solution beyond any particular desired point, the steam and vapors after leaving the tar scrubber may be somewhat cooled or the caustic or carbolite solution may be cooled by means of cooling coils, or water may be continuously or intermittently added to the caustic-carbolite solution to maintain the desired concentration. Under such conditions, part of the oil vapors in the steam may be condensed and may remain with the carbolite. They may be continuously separated off and returned to the dephenolized tar or may be kept separate as a secondary product of the process.

The caustic soda absorber can be constructed in stages so that a completely saturated carbolite can be made in the first stage, or in the lower compartment of a series of compartments while there is still an excess of caustic in the second or upper stage. In this way, the caustic solution can be exhausted of caustic soda and at the same time the tar acid vapors extracted with substantial completeness from the gases.

A selective extraction of the phenols or tar acids from the admixed gases and vapors can be effected by installing and employing several caustic scrubbers and carrying out the scrubbing operation in stages. If, for example, a carbolite rich in phenol and a second carbolite rich in higher boiling tar acids, including cresols, is desired, a three-stage absorber or scrubber can be employed with the supply of caustic to the lower or first section or scrubber, equivalent only to the phenol entering the system in the steam or other inert gas or vapor being circulated. The carbolite will be allowed to be completely saturated and to build up to the maximum percent of the phenols before any is withdrawn. Phenol, being more strongly acidic than the higher phenols, e. g. cresols and xylenols, will replace these higher phenols from their combination with caustic soda, so that, when the caustic soda is consumed, and a carbolite solution is produced, the passing of

additional gases carrying phenol and higher phenols will result in the driving off of higher phenols and the absorption of phenol until the carbamate solution in the lower section will be greatly enriched in sodium phenolate, while the higher phenols will be absorbed in the higher section. With a multi-stage operation of this kind, it is possible to produce carbolates predominating in phenol, the cresols, the xylenols, etc. If still more selective extraction is desired, the carbamate absorber may be constructed in a larger number of stages, e. g. five or six, and a plurality of different tar acid fractions obtained.

The recovery of tar acids from tars, according to the present invention, may be carried out batch-wise or continuously, that is, from successive batches of tar, or from tar which is continuously supplied and with continuous discharge of the dephenolized tar, and likewise with batch-wise or continuous operation of the caustic soda absorber, using successive batches of caustic soda solution for forming phenolates, or supplying additional fresh caustic continuously and withdrawing the carbamate solution continuously. With batch-wise operations, the caustic absorbers may be installed in parallel or at least in duplicate with piping arranged for allowing saturated carbolates to be produced first in one and then in the other absorbers. At tar distillation plants, particularly at continuous tar distillation plants, with continuous supply of tar to the dephenolizing scrubber, the system of dephenolizing can be made a part of the distillation unit, so that it will function continuously and require no labor in addition to that normally required for the continuous distillation.

At plants employing continuous pipe coil stills, with heating of the tar in a pipe coil, or in a series of pipe coils, which discharge into vapor separating chambers, the dephenolizing scrubber may be one of the vapor separating chambers and the dephenolizing operation can be carried out continuously as a part of the continuous pipe coil still distillation, using the tar when it has been heated to the proper temperature for the dephenolizing treatment and subsequently heating the dephenolized tar to a higher temperature to complete its distillation. In such a case, the steam or other inert gas would be recirculated from the vapor separating chamber or from the still through a caustic scrubber, and the steam and admixed gases then cooled to separate neutral oil, or recirculated. In such operations, steam may or may not be employed, and it may be found desirable to use a vacuum in some cases, although the process may, if desired, be worked under pressure. Where the removal of neutral oils along with the tar acid vapors is sufficient to leave a pitch product which does not require further distillation, the neutral oils can be recovered from the gases after leaving the caustic absorber. So also, where such a pitch is produced, the neutral oils can be returned to it after the extraction of tar acid vapors, thus giving a tar of similar composition to the original tar except for the removal of tar acids therefrom.

The invention will be further described in connection with the accompanying drawings, which are in the nature of flow sheets and are more or less conventional and diagrammatic in character and which illustrate various arrangements of apparatus for carrying out the invention, but it will be understood that the invention is not limited thereto.

75 In the accompanying drawings.

Fig. 1 shows one system of apparatus adapted for carrying out the invention;

Fig. 2 shows a modified system in which multi-stage extraction of the tar is provided for;

Fig. 3 shows an apparatus having a condenser arranged in the recirculating gas line to condense neutral oils from the recirculating gases;

Fig. 4 shows a simple fire-heated still combined with apparatus for recovering tar acids directly from the tar in the still;

Fig. 5 shows a two-stage absorbing tower;

Fig. 6 shows an apparatus with a three-stage absorption tower for fractionally extracting phenols; and

Fig. 7 shows the invention combined with a pipe coil still for distilling tar continuously.

In the various figures, the corresponding parts are indicated by the same reference numerals, in some cases with reference letters appended thereto.

Referring to Fig. 1, tar from a suitable storage tank 1 is pumped by pump 2 through the line 3 to a preheater comprising a pipe coil 4 arranged in a heating furnace or chamber 5 and heated by waste heat or otherwise. The preheated tar passes through the line 6 to the top of a scrubber 7 in which the tar is subjected to a counter-current flow of steam or other inert gas. The tar after the dephenolizing treatment passes through the line 8 to a place of storage or to distillation equipment, etc.

The scrubber 7 may be a tall packed tower which provides for intimate contact of the tar flowing downwardly therethrough and the gases passing upwardly therethrough. The packed section of the tower is indicated at 9. A current of steam or other gas is forced by blower 10 through line 11 to the bottom chamber 12 at the bottom of the scrubber tower and passes upwardly through the packed section 9 to the chamber 13 at the top of the tower from which the gases and vapor pass through the line 14 to the bottom of a dephenolizing tower 15 and pass upwardly therethrough countercurrent to a caustic soda solution. The gases freed from tar acid vapors escape through the line 16 and may be recirculated by the pump 10. Where the gases are not recirculated, they may be drawn off through the line 24 and fresh steam or other gas supplied to the blower 10 through line 50, or any desired portion of the gases and vapors can be led out through the line 24 and the remainder recirculated and make-up gases admitted through the line 50. Fresh caustic solution is supplied to the top of the dephenolizing tower 15 through the line 17 and provision is made for drawing off the phenolate solution from an overflow 18 at the bottom of the tower. Provision is also made for recirculating the caustic solution through the circulating line 20 by means of the pump 21 and discharging it at 22 into the top of the tower. A heat interchanger 23 is shown in the line 20 for use if desired to heat the circulating caustic solution to maintain it at the proper temperature, or, where the gases and vapors entering the tower are at a much higher temperature than the caustic solution, the solution may be cooled in the heat interchanger to avoid too great evaporation of water from it by the hot gases. The carbamate solution is collected in receiver 19. The tar acids or phenols can be recovered from the carbamate, for example, by treating with carbon dioxide which sets free the tar acids or phenols and forms sodium carbonate which can be recausticized for further use in the process.

The apparatus of Fig. 2 is similar to that of Fig. 1 but provides a two-stage dephenolizing treatment in which the partly dephenolized tar escaping from the first dephenolizing scrubber 7 through the line 8 is passed through a reheat coil 5a and then through a second dephenolizing tower 7a where it is subjected to a further and similar dephenolizing treatment, the resulting dephenolized tar escaping through the line 8a to a place of storage or of distillation, etc. In this arrangement, part of the phenols, and particularly the lower boiling phenols which have a stronger acid reaction, are largely extracted, while further extraction will take place in the second dephenolizing tower.

The arrangement of Fig. 3 has a fractionating condenser 25 arranged in the line 16 leading from the top of the dephenolizing tower so that the hot gases and vapors can be cooled to condense more or less of the neutral oil vapors therefrom to give a neutral oil condensate which escapes through the line 26, after which the gases and vapors are returned through the blower 10 and the line 11 to the scrubber 7.

In Fig. 4, a simple fire-heated still is shown at 7 with provision for forcing steam or other gas through the body of hot tar in the still. The resulting gases and tar acid oil vapors pass through the line 14 to the bottom of the caustic scrubber 15. The gases and vapors escaping from the top of the tower pass through a condenser 25 at a regulated temperature, the condensate collecting in the receptacle 26 and being drawn off therefrom while the uncondensed vapors and admixed gases return through the line 27 to the blower 28 and are forced through the perforated pipe 29 into the bottom of the body of hot tar in the still. When the tar has been heated to a suitable temperature, e. g. around 100° C. or somewhat higher, steam or other gas is forced through the body of tar to remove tar acid oil vapors and the resulting vapors and gases pass through the caustic absorber, then through the condenser to condense part of the neutral oil vapors, and the uncondensed vapors and admixed gases are then returned for recirculation to the still. After the tar acids have been driven off to the desired extent, the recirculation can be discontinued and the still heated to a higher temperature and the distillates carried over through the line 51 to the condenser 52. In this case, more or less of the light neutral oils can be recovered during the dephenolizing treatment and drawn off from the receiver 26, while the oils subsequently distilled from the tar will be collected in the usual way by condensation in the condenser 52.

In Fig. 5 a two-stage caustic scrubber is shown in the form of an upper and lower section 15c and 15b separated by a collecting plate 30, through which the gases and vapors are permitted to pass upwardly and through which the caustic solution can overflow from the upper to the lower section. In this tower, the caustic solution is supplied to the top of the tower and the carbolite solution drawn off from the bottom. Provision is made for recirculating both the caustic solution and the carbolite in the respective sections of the tower, while the excess will overflow from the top to the bottom section. The gases laden with tar acid oil vapors will enter the lower section and may completely saturate the caustic solution with carbolite. The removal of tar acid oil vapors will be completed in the upper section to which fresh caustic soda solution can be continually supplied.

The apparatus of Fig. 6 has a three-stage absorber so that, for example, carbolites predominating in phenol, the cresols, the xylenols, etc. can be produced. Provision is made for supplying fresh caustic both to the upper section 15d and to the lower section 15f and for drawing off carbolite solution from the bottom of the middle section and also from the bottom of the lower section through outlet lines 18c and 18f. If, for example, a carbolite rich in phenol and a second rich in the higher boiling acids, including cresols, is desired, the caustic solution supplied to the lower or No. 1 section through pipe 17f will not be more than that equivalent to the phenol entering the system admixed with the steam or other inert gas. The carbolite will be allowed to be completely saturated and to build up to the desired percent phenol before any is withdrawn. From that point on, caustic equivalent only to the phenol or slightly less if the maximum enrichment in phenol is desired will be fed in continuously and carbolite withdrawn continuously from the bottom of the lower compartment. The intermediate compartment 15e will be operated in the same manner except that the caustic stream supplied through the pipe 17e will enter the top of the third or upper compartment and overflow to the intermediate compartment in which saturated carbolite will be present at all times. This carbolite will be withdrawn continuously at 18e and will contain all of the acids of boiling point above phenol, or will be low in phenol and high in the higher boiling acids. The carbolite from the lower compartment will be rich in phenol, but may contain some cresols and higher boiling acids. With a larger number of stages, a more selective extraction of the tar acids can be obtained by proceeding in a similar manner.

In the apparatus of Fig. 7, the dephenolizing tower 7 is arranged between a preliminary pre-heating pipe coil 4 and a second pipe coil 41 so that, after the tar has been subjected to the dephenolizing treatment in the tower or scrubber 7 it can be pumped by the pump 40 through the line 8 to the heating coil 41 and there heated to a high temperature and then discharged into the vapor separating chamber 42, from which the pitch is withdrawn through the outlet 43 to a receiver 46 while the oil vapors distilled from the tar pass through the line 44 to the water condenser 45 and are collected in receiver 47. The heat supplied to the tar for preheating it prior to dephenolizing, is employed in the subsequent further heating of the tar so that, in the subsequent heating, it is only necessary to heat the tar from its preheated condition to that to which it is to be subjected for the final distillation. The dephenolizing treatment in this case is combined as a part of the pipe coil distillation, so that the tar is dephenolized after it is preheated and before it is further heated for the main distillation.

In the diagrammatic drawings, heat inter-changers or heating devices for the circulating gases and for the circulating caustic solution are omitted, except for the heat interchanger shown in Fig. 1. So also, the means for heating the tar or for supplying hot tar is omitted in all of the figures except Figs. 1, 4, and 7. It will be understood that the tar will be employed in a suitably heated state, or will be preheated in some suitable manner, as hereinbefore pointed out, and that additional heating or cooling of the circulating gases and of the carbolite solution may be employed, and that, in those figures which show re-

circulation of the gases without provision for the supply of fresh gases and the withdrawal of part or all of the gases, additional gases may be supplied as required, and part or all of the gases can be withdrawn instead of being recirculated, in which case the withdrawn gases and vapors will be cooled to condense the oils therefrom.

The further treatment or disposal of the tar, after the dephenolizing treatment, is not shown except in the case of Figs. 4 and 7, but it will be understood that the tar which is in a heated condition as it leaves the dephenolizing scrubber can be passed to a tar still to be there distilled so that its contained heat can be utilized, or that the tar can be otherwise disposed of. At tar distillation plants, the present process can advantageously be combined with the distillation process by subjecting the tar to a dephenolizing treatment after it has been heated to the proper temperature and before it is further heated for further distillation.

The temperature to which the tar is heated before it is subjected to the dephenolizing treatment can be varied, depending upon the pressure under which the scrubber is operated, i. e. whether at atmospheric pressure, under increased pressure, or under a pressure lower than atmospheric, the volume of inert gases circulated through the scrubber or still, the extent to which the higher tar acids are to be driven off and recovered, and like considerations. Where steam is employed and circulated or recirculated through the tar scrubber, it will be evident that the temperature of the tar should be above the temperature of condensation of the steam, and that the temperature of the caustic scrubber should also be above the temperature of condensation of the steam. It is desirable, although not entirely necessary, to maintain the caustic scrubber and the tar scrubber at the same or similar temperatures, particularly where the gas is recirculated repeatedly through the two scrubbers. The maximum temperature of the gases and vapors leaving the caustic scrubber will be limited by the presence of caustic solution which will tend to cool the gases and vapors to a temperature approximating that of the solution. Temperatures of the tar in the tar scrubber and of the recirculating gases of around 125 to 175° C. are suitable, although the temperatures can be materially lowered when the process is carried out under reduced pressures or with the use of inert gases other than steam. At lower temperatures the volume of steam or other inert gas recirculated must be increased per unit quantity of tar acids recovered.

The present process has the advantage, among others, of giving the tar acids directly without the separate recovery, shipment and extraction of a large amount of oils, thus making unnecessary the provision of large carbolic oil storage and extraction systems. The process also enables tars to be treated for the recovery of higher percentages of tar acids than can be economically recovered by present day processes due to the troublesome handling of higher boiling heavy oils. The process also yields carbolates and tar acids of high quality, low in sulfur compounds and low in distillation residue, while it enables caustic losses to be reduced to a minimum and equipment required to be materially reduced. The process is also of value for recovering tar acids from tar acid oils, particularly those which are contaminated with tar. With low temperature tars or tarry oils, which are unusually high in tar acids, the present process enables

a high yield of the tar acids to be recovered directly from the tar, and with fractional separation of higher and lower boiling acids, if desired.

It will be understood that variations and modifications can be made in the process as hereinbefore described, without departing from the spirit and scope of the invention.

I claim:—

1. The method of recovering tar acids from tar, which comprises passing inert gases into intimate contact with hot tar to effect vaporization of tar acid oils, and effecting selective and fractional extraction of tar acids from the resulting admixed gases and vapors by passing the same through a series of alkaline solutions and regulating the solutions to effect selective and fractional extraction of the tar acids from the admixed gases and vapors.

2. The method of extracting tar acids from admixture with inert gases in vapor form, which comprises passing the gases into the first of a plurality of chambers and then thru the other chambers in series, removing the extracted gases from the last of the chambers, introducing fresh caustic into the last chamber, supplying the other chambers with caustic mixed with carbolite formed by action of caustic on the tar acids in the gases, recycling a portion of the carbolite through the first chamber and withdrawing carbolite from the first chamber.

3. The method of extracting tar acids from admixture with inert gases in vapor form, which comprises continuously bringing into contact with the gases a solution comprising caustic and carbolite recycling at least a portion of the resulting solution and adding fresh caustic to the recycled solution.

4. The method of extracting tar acids from admixture with inert gases in vapor form, which comprises extracting the tar acids by an alkaline solution recycling at least a portion of the alkaline solution for further extraction of tar acids and increasing the temperature of the solution before reuse.

5. The method of extracting tar acids from inert gases in vapor form, which comprises continuously introducing into a chamber through which a mixture of the tar acids and gases are passed, fresh caustic solution and reused solution containing carbolite, withdrawing the resulting solution and reusing a portion in the chamber for the extraction of tar acids.

6. The method of extracting tar acids from admixture with inert gases in vapor form, which comprises producing a carbolite rich in phenol by bringing into contact with the gases and tar acid vapors a caustic solution containing an amount of caustic not in excess of that required to neutralize all of the phenol and then extracting higher tar acids from the resulting mixture of gases and vapors by bringing an alkaline solution into contact therewith.

7. The method of selectively absorbing tar acids from a mixture of vapors comprising phenol and higher tar acids which comprises passing said vapors in contact with a caustic solution containing insufficient caustic to combine with all of the tar acids in the gas contacted therewith, passing the thus treated gas in contact with a second caustic solution to separately absorb tar acids unabsorbed by the first caustic solution, whereby phenol and higher tar acids are selectively absorbed in said caustic solutions, and separately withdrawing said caustic solutions from contact with said vapors.

8. The method of recovering tar acids from tar, which comprises repeatedly passing inert gases including neutral oil vapors into intimate contact with hot tar to effect selective vaporization of tar acid oils, and then through a series of alkaline solutions and regulating the contact of the gases with each of the solutions so as to effect selective and fractional extraction of the tar acids from the admixed gases and vapors and recycling at least a portion of the inert gases together with neutral oil vapors into contact with the tar.
9. Apparatus for the selective distillation of tar comprising a dephenolizer, means for introducing liquid hydrocarbon material thereto and withdrawing liquid residue therefrom, an extractor, means for passing gases from the dephenolizer to the extractor and means for passing gases from the extractor back to the dephenolizer, said extractor comprising a plurality of chambers each equipped with means for spraying liquid into the gases passing therethrough, inlets for fresh caustic and liquid draw-offs associated with a plurality of said chambers and means for blending with the fresh caustic introduced into each of a plurality of said chambers liquid previously contacted with the gases in the respective chambers, that part of each chamber with which the liquid contacts being constructed of caustic-resistant material.
10. Apparatus for the selective distillation of tar comprising a dephenolizer, means for introducing liquid hydrocarbon material thereto and withdrawing liquid residue therefrom, an extractor, means for passing gases from the dephenolizer to the extractor and means for passing gases from the extractor back to the dephenolizer, said extractor comprising a plurality of chambers each equipped with means for spraying liquid into the gases passing therethrough, inlets for fresh caustic and liquid draw-offs associated with a plurality of said chambers and means for blending with the fresh caustic introduced into each of a plurality of said chambers liquid previously contacted with the gases in the respective chambers, that part of each chamber with which the liquid contacts being constructed of caustic-resistant material.

fresh caustic into the last chamber of the series and means for spraying into each preceding chamber of the series liquid resulting from the spraying of the gases therein, those parts of the extractor with which the liquid comes in contact being constructed of caustic-resistant material.

10. Apparatus for the selective distillation of tar comprising a dephenolizer, means for introducing liquid hydrocarbon material thereto and withdrawing liquid residue therefrom, an extractor, means for passing gases from the dephenolizer to the extractor and means for passing gases from the extractor back to the dephenolizer, said extractor comprising a plurality of chambers each equipped with means for spraying liquid into the gases passing therethrough, inlets for fresh caustic and liquid draw-offs associated with a plurality of said chambers and means for blending with the fresh caustic introduced into each of a plurality of said chambers liquid previously contacted with the gases in the respective chambers, that part of each chamber with which the liquid contacts being constructed of caustic-resistant material.
